UNITED STATES PATENT OFFICE

ALEXANDER WEINBERG, OF NEW YORK, N. Y.

GAME APPARATUS

Application filed April 23, 1930. Serial No. 446,712.

Objects of my invention are to provide game apparatus which will call for the exercise of skill on the part of the player, will involve chance, will afford amusing entertainment created by movements or motions of moving elements of the apparatus, and simplicity and inexpensiveness of structure.

My invention consists in whatever is described by or is included within the terms or scope of the appended claims.

In the drawings:—

Fig. 1 is a perspective view of game apparatus embodying my invention;

Fig. 2 is a vertical section;

Fig. 3 is a detail view in longitudinal section of the missile propelling device.

Apparatus embodying my invention comprises a suitable board, a missile propelled, or thrown, by the player and objectives for the missile consisting of an object or objects of suitable design that rest or stand loose upon or unattached to a suitable support so that by the impact of the missile the object will be displaced bodily and fall upon or be received by either a score value part of the board or a negative score or non-score value part thereof. Preferably the missile is projected by a simple mechanical device, or it may be a ball corresponding to a marble to be shot by the thumb and finger, as in playing marbles.

The "board" shown includes a horizontal platform, 10, of rectangular form, at the far end of which is a wall, 11, which extends upward and rearward and cross-wise of the board to the upper edge of which one or more horizontal flat fingers, 12, are attached that reach forward of and overhang said wall, so that an accurately directed missile moving rearward over the platform, 10, and ascending the inclined wall, 11, will strike a smart blow on the underside of a selected finger, 12. The fingers, 12, are flexibly connected or attached to the wall, 11, so that they will move upward under a smart blow and thereby an object, 13, resting loosely thereon (which may have the form of a comical eccentrically weighted human figure) will be thrown upward and rearward in a sudden movement and a move-

ment which due to gyrations of the body will be droll. The body movements by reason of their suddenness are amusing.

In rear of and somewhat below the figure supporting fingers, 12, is a transversely extending, horizontal table, 14, on which a dislodged figure may fall and in such table there are one or more holes, 15, marked with score values, into which a figure may fall. And at the rear edge of the table, 14, is a vertical wall, 16, for the double purpose of preventing the figure being thrown off the board, and supporting score value pockets or baskets, 17, into which the dislodged figure may fall.

On the platform, 10, forward of the lower edge of the inclined guiding wall, 11, may be areas, 18, marked with minus or negative score values on which the dislodged figures may fall.

The level of the table, 14, in rear of the figures is sufficiently below the figure supports, 12, to prevent a figure falling on the table, 14, or against the rear wall, 16, by any forward movement reaching and dislodging a figure on its support, 12.

As shown in the drawings, the entire board may be made of two elements or members, one a rectangular sheet of cardboard, or other material, to constitute the platform, 10, and the other a single sheet of similar material folded or bent, as shown in the drawings, that includes all of the parts from the wall, 11, to the wall, 16, excepting, of course, the fingers, 12 and the baskets or pockets, 17, which are separately made. The fingers, 12, may be of a simple strip of cardboard such as "Fiber-hide" bent to an L-shape to provide a shank for attachment, as by adhesive, to the down-turned upper edge of the wall, 11, and to provide the horizontal figure support, 12, when so made sufficient spring or elasticity being provided to secure the return of the supporting finger, 12, to normally horizontal position after it has been struck or moved by the sudden impact of a missile.

An excellent form of missile propelling device is shown in the drawings. It con-

sists of a tube or barrel, 19, with a spring-actuated plunger, 20, on one end of a handle, 21, which barrel on the top has a hole, 22, through which a ball or marble, 23, may be passed when the plunger, 20, is retracted to place the spring in compression, and thereby the marble placed in front of the plunger, 20, so that upon release thereof the spring will forcibly throw the marble forward. At its bottom, the tube or barrel, 19, is secured by a vertical pivot, 24, to the platform, 10, at its forward edge, so that the propeller may be swung horizontally to direct or aim it towards a particular figure-supporting finger, 12.

While the embodiment of my invention shown in the drawings and described in detail is a very excellent one, it is to be understood that structural and functional changes may be made therefrom and, therefore, my invention does not exclusively consist in that particular embodiment but consists in whatever falls within the legal meaning or scope of the appended claims.

What I claim is:—

1. Game apparatus comprising a missile receiving and directing surface that extends upward, a movable figure support above the bottom of such surface, and a figure movable bodily from such support when a blow is imparted to the underside of the support by a missile passing upward over such surface.

2. Game apparatus comprising a missile receiving and directing surface that extends upward, a movable figure support above the bottom of such surface, a figure movable bodily from such support when a blow is imparted to the underside of the support by a missile passing upward over such surface, and score value means to which the dislodged figure may move.

3. Game apparatus comprising a missile receiving and directing surface that extends upward, a movable figure support above the bottom of such surface, and a figure movable bodily from such support when a blow is imparted to the underside of the support by a missile passing upward over such surface, said figure support being a vertically movable spring device.

4. Game apparatus comprising a horizontal platform over which a missile may be propelled, a missile directing surface extending upward and rearward from such platform and extending crosswise thereof, a series of movable figure supporting fingers projecting from the upper part of such surface forwardly with their undersides exposed to a missile traveling upward over such surface and a figure resting upon each finger and bodily movable therefrom when the finger is moved upward by the impact of a missile on the underside thereof.

5. Game apparatus comprising a horizon-

tal platform over which a missile may be propelled, a missile directing surface extending upward and rearward from such platform and extending crosswise thereof, a series of movable figure supporting fingers projecting from the upper part of such surface forwardly with their undersides exposed to a missile traveling upward over such surface, a figure resting upon each finger and bodily movable therefrom when the finger is moved upward by the impact of a missile on the underside thereof, and score value devices to receive a dislodged figure situated in rear of said surface.

6. Game apparatus comprising a horizontal platform over which a missile may be propelled, a missile directing surface extending upward and rearward from such platform and extending crosswise thereof, a series of movable figure supporting fingers projecting from the upper part of such surface forwardly with their undersides exposed to a missile traveling upward over such surface, a figure resting upon each finger and bodily movable therefrom when the finger is moved upward by the impact of a missile on the underside thereof, a horizontal table in rear of the movable figure support and a vertical wall extending above such table.

In testimony whereof I hereunto affix my signature.

ALEXANDER WEINBERG.
